(57) **CLAIM**

The ornamental design for a footwear, as shown and described.

DESCRIPTION

FIG. 1 is a perspective view of a footwear showing my new design;

FIG. 2 is a close-up front perspective view thereof;

FIG. 3 is a close-up back view thereof;

FIG. 4 is a left side view thereof;

FIG. 5 is a right side view thereof;

FIG. 6 is a top view thereof; and,

FIG. 7 is a bottom view thereof.

The dash-dot broken lines in the drawings represent portions of the footwear that form no part of the claimed design. The dash-dash broken lines in the drawings represent stitching that forms no part of the claimed design.

1 Claim, 7 Drawing Sheets
